SEWING PAD

Martha C. Thillard, New York, N. Y.

Application March 9, 1939, Serial No. 260,712

1 Claim. (Cl. 223—110)

This invention relates to a work-holder for use in sewing, and more particularly to a pad which may be secured to a person's leg so that fabrics being sewed can be pinned thereto to hold them in position during sewing. In sewing fabrics held in the lap, and particularly in such operations as hemming, it is usually desirable to secure one edge of the fabric in some manner, holding the other end of the fabric with one hand and performing the sewing operation with the other hand. Stretching the edge of the fabric, or a section of the edge of the fabric, in some manner makes it possible to obtain a more even hem than would be possible otherwise. The free edge of the material is sometimes held between the knees, tucked under one leg, or it may be pinned to the skirt for this purpose, but such a support for the material is insecure at best, and may damage the clothes. This is particularly true when the fabric is pinned to the skirt because the pins frequently catch a thread of the stockings underneath and thus start runs in the stockings.

My invention is designed to overcome these difficulties and provides a secured fixed support to which fabrics may be pinned during sewing.

It is an object of this invention to provide a pad to which fabrics may be pinned, such pad having a means for securing it to one's leg.

Another object of the invention is to provide a band in the nature of a round garter having a padded portion held securely in place so that fabrics may be pinned thereto during sewing, either directly to the pad or through the skirt.

Other objects will be apparent from a more detailed description of the embodiments of my invention illustrated in the drawing, in which

Figure 1 is a perspective view of a work-holder in accordance with my invention, the dotted lines indicating the portion of the leg to which it may be secured just above the knee.

Figure 2 is a bottom plan view of the work-holder in collapsed position.

Figure 3 is a view similar to Figure 2 but showing an adjustable strap for varying the circumferential length of the band.

Referring to the drawing, numeral 10 indicates a band constructed of suitable fabric or other material, having a relatively wide padded portion 11. Padded portion 11 also is preferably made fairly thick and may be stuffed with any of various fabrics or materials held in place by the crossed lines of stitching 12 in order to provide a solid pad to which fabrics may be readily secured with pins. While this padded portion 11 may be made very thick, it is preferably padded just suffi-

ciently to hold pins securely and protect the stocking underneath. The pad thus may be made to lie flat without bulging if it should be worn under the skirt. The main portion of the band 10 may be finished at the edges with suitable binding tapes 13. One section of the band, preferably spaced circumferentially from the padded portion 11, may be made of elastic material 14. This elastic material 14 is preferably fairly wide in order to be comfortable, and may be secured to the ends of the main band 10 by the stitching 15.

Instead of providing an elastic section 14, an adjustable strap 16 (Figure 3) may be fixed to one end of the band 10, as at 17, and doubled over through a suitable elongated ring 18 secured to the other end of the band 10. The other end of strap 16 may be secured to the central member of the buckle 19. Buckle 19, which may be of any suitable construction adapted to slide on the main portion of the strap 16, is thereby used to adjust the effective circumferential length of the band. The strap 16 may be made of elastic or inelastic material.

In operation, the band 10, if not of the proper size, may be adjusted to the size needed and slipped on over the leg to a point preferably just above the knee. The band is adjusted so that the padded portion 11 is uppermost. The piece of fabric to be hemmed or otherwise sewed is then pinned to the padded portion 11 either directly, if the skirt has been pulled up to expose the band 10, or the fabric may be pinned to the padded portion 11 through the skirt. The edge of the fabric may then be pulled out away from the work-holder with one hand while it is being sewed with the other hand.

This pad is held securely in place and thus provides a firm support for the fabric to be sewed. Fabrics may thus be stretched out as tightly as desired by pulling with the left hand preparatory to and during sewing with the right hand. Even though the fabric is pinned to the padded portion 11 through the skirt, no strain is placed on the skirt by reason of the firm support for the pin underneath it. In addition, the pad prevents the pins from touching the stockings and thus saves on stockings.

Many modifications and variations of my invention will be apparent to those skilled in the art. For example, the work-holder may be made with a suitable fastening so that it can be fastened around the leg without the necessity of slipping it on over the foot. Other means for

securing the work-holder to the leg may be employed.

A particular advantage of my work-holder is its invisibility when a worker wearing it stands up. Since the work-holder is then covered by the skirt, each time the sewing operation may be interrupted.

The terms and expressions which I have employed are used as terms of description and not of limitation, and I have no intention, in the use of such terms and expressions, of excluding any equivalents of the features shown and described or portions thereof, but recognize that various

modifications are possible within the scope of the invention claimed.

I claim:

As an article of manufacture, a work-holder for use in sewing comprising a band constructed and arranged to be held in a fixed position on a worker's leg, and a relatively flat pad associated with and wider than said band and adapted to have fabric pinned thereto, said pad being sufficiently flat to avoid bulging when worn under a skirt and sufficiently solid to hold a fabric pinned thereto in a fixed position.

MARTHA C. THILLARD.
